UNITED STATES PATENT OFFICE.

PIETRO IACOVINO, OF NEW YORK, N. Y.,

ARCH-SUPPORT FOR SHOES.

1,089,378.

Specification of Letters Patent.

Patented Mar. 3, 1914.

Application filed April 22, 1913. Serial No. 762,780.

To all whom it may concern:

Be it known that I, PIETRO IACOVINO, a subject of the King of Italy, and a resident of the city of New York, borough of Manhattan, in the county and State of New York, have invented a new and Improved Arch-Support for Shoes, of which the following is a full, clear, and exact description.

10 This invention relates to arch supports for foot wear, and has for an object to provide an improved structure which may be readily applied to any footwear and at any time.

Another object of the invention is the provision of an improved support of such a shape and with suitable bracing members for supporting the arch of the foot, the entire structure being also formed so as to be readily inserted in a shoe after the same

20 has been completed.

In carrying out the objects of the invention, a supporting arch structure is provided, formed with a reinforcing metallic strip rigidly secured in place, the entire 25 structure being designed to be readily inserted, and if desired removed from a finished shoe. The arch is formed of any desired material, as for instance a plurality of strips or layers of leather with a padding 30 of rubber or other cushioning means at one point, and a stiffening strip or plate of metal immediately below the arch or curved portion of the device. Arranged on one 35 side of the arched or curved device is a side or up-turned member for bracing the same.

A practical embodiment of the invention is represented in the accompanying drawings forming a part of this specification, in which similar characters of reference indicate corresponding parts in all the views.

Figure 1 is a bottom plan view of the bottom of the invention; Fig. 2 is a side view of the structure shown in Fig. 3; Fig. 3 is a sectional view approximately on the 45 line 3—3 of Fig. 2; and Fig. 4 is a sectional view through Fig. 2 on the line 4—4.

Referring to the accompanying drawings by numerals, 1 indicates a body or main strip of material, preferably of leather. 50 The strip 1 is formed of leather of an appreciable thickness so as to have more or less body or bracing qualities. This strip is pressed so as to present a substantially central upwardly curved portion 2, and a 55 slightly downwardly curved portion 3 at one end, and at the other end a slightly

downwardly curved end 4 is presented. The end 4 tapers to a point at 5. A cover of comparatively thin flexible leather 6 is provided, which extends from one side of the base 1 to the other and also near the center part in an upward direction for forming a side bracing member 7. It will be observed that the body 1 is slightly concaved transversely with edge 8 curved up somewhat so 60 as to hold the foot against lateral movement. A bracing strip 9 is provided at the upwardly bowed central part 2. The strip 9 is provided with a tongue 10 having spreading or diverging wings 11 and 12 near the rear 65 of the base 1. This causes the flexible tongue portion 10 to be rigidly held in place but to properly brace the arch of the foot. By reason of the use of the comparatively narrow strip 10 the part of the brace 9 which 70 supports the arch is comparatively flexible and will therefore give or yield while maintaining a proper bracing action for the arch. The bracing member 9 may be held in place 75 by any desired means, as for instance rivets 80 13. Preferably one or more pins 14 are provided for holding the entire device against movement when placed in the shoe, the pins 14 being forced into the bottom of the shoe at the time the arch device is placed in position. 85

Arranged near the front of the base 1, is a cushioning member 15, preferably of good rubber which is of considerable thickness centrally and tapers toward each end 16, 90 while tapering from a thick side (Fig. 3) to a point 17 transversely. This provides for a proper cushioning of the ball of the foot where more or less of the strain is produced. 95

Arranged beneath the end 4 of body 1, and beneath the cushion 15, is a comparatively thin strip of leather 18 which may be securely placed in any desired manner, and which extends forwardly until it joins with 100 the upper strip 6, where strips 6 and 7 are secured together in any desired manner, as for instance by a line of stitching.

In use, the device is intended to be inserted into a finished shoe and after proper adjustment locked in place by having the pins 14 driven into the shoe. In this way if the ordinary shoe is not provided with the proper arch support, one may be supplied without re-making the shoe, and at a minimum expense. Also the curve 2 may be 105 varied so that parts of the device may be 110

used having different curvatures so as to accommodate or fit the arches of different shaped feet.

Having thus described my invention I claim as new and desire to secure by Letters Patent:-

1. In an arch support of the class described, a body and a metallic reinforcement therefor bowed from one end to the other, said metallic reinforcement being substantially T-shaped, the two arms of the T extending transversely of the body near the end of the same and the trunk of the T extending longitudinally of the body.
- 10 2. In an arch support of the class de-

scribed, a body and a metallic reinforcement therefor, said metallic reinforcement being formed with a body extending substantially centrally and longitudinally of said first mentioned body, said body being bowed from one end to the other, and with a pair of transversely extending arms.

In testimony whereof I have signed my name to this specification in the presence of two subscribing witnesses.

PIETRO IACOVINO.
